UNITED STATES PATENT OFFICE.

TILLMAN CAHN, OF ELKINS PARK, PENNSYLVANIA, ASSIGNOR TO PIONEER SUS-PENDER COMPANY, A CORPORATION OF PENNSYLVANIA.

DESIGN FOR A GARTER.

60,084.

Specification for Design.

Patented Dec. 27, 1921.

Application filed July 14, 1920. Serial No. 396,321. Term of patent 14 years.

To all whom it may concern:

Be it known that I, TILLMAN CAHN, a citizen of the United States, residing at Elkins Park, in the county of Montgomery, State of Pennsylvania, have invented a new, original, and ornamental Design for a Garter, of which the following is a specification, reference being had to the accompanying drawings, forming part thereof.

Fig. 2 is a fragmentary elevation, in the closed position.

I claim:

The ornamental design for a garter as shown.

TILLMAN CAHN.
